UNITED STATES PATENT OFFICE

2,688,288

ADJUSTABLE HANGER STRAP FOR SUBWAY CARS AND THE LIKE

Moses H. Harris, New York, N. Y.

Application January 30, 1951, Serial No. 208,614

5 Claims. (Cl. 105—354)

1

This invention relates to hand straps for vehicle passengers, and is particularly directed to a hand strap for use in subways, trains and busses which may be held by standing riders.

An object of this invention is to provide a device of the character described, which shall be adjustable to accommodate riders of various heights and reach.

Another object of this invention is to provide an adjustable and extensible hand strap of the character described, which may be lowered to various distances so as to accommodate passengers having a shorter reach.

Still another object of this invention is to provide in a device of the character described, spring means to raise the hand strap to bring the strap to various adjusted positions.

Yet another object of this invention is to provide a strong, rugged and durable device of the character described, which shall be relatively inexpensive to manufacture, yet practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawing in which are shown various illustrative embodiments of this invention

Fig. 1 is a side elevational view of a hand strap embodying the invention;

Fig. 2 is a front elevational view thereof;

Fig. 3 is a cross sectional view taken on the line 3—3 of Fig. 2;

Fig. 4 is a cross sectional view taken on the line 4—4 of Fig. 3;

Fig. 5 is a view similar to Fig. 3 but showing the hand strap adjusted for a passenger with a smaller reach;

Fig. 6 is a view similar to Fig. 3, but illustrating a modified construction.

Referring now in detail to the drawings, 10 designates a hand strap device embodying the invention. The same comprises a sleeve 11 having end walls 12 formed with circular through-openings 13 through which extends a usual horizontal supporting bar 14, fixed in any suitable manner to a subway car or bus.

The sleeve 11 has a part-cylindrical wall 15 interconnecting the end walls 12. The part-cylindrical wall 15 has end edges 16 and 17 and is formed with a cut out therebetween.

2

Surrounding the bar 14 and disposed within the sleeve wall 15 is a usual torsion spring 18 which normally tends to rotate the hand strap from the full line position of Fig. 1 to the dotted line position of said figure, in the well known manner.

Extending from the sleeve wall 15 is a ribbed portion 19 and extending therefrom is a rod 20. The lower end of the rod has a transverse through-opening 21 through which extends a transverse pin 22. The pin 22 extends beyond the rod 20, as at 23, for the purpose hereinafter appearing.

Fixed to the lower end of the rod 20 is a circular disk or collar 25. The collar 25 has through-openings through which the pin 22 passes and said pin ends extend beyond the collar 25.

Slidably and rotatably mounted on the rod 20 is a member 30. Said member 30 comprises a cylindrical wall 31. The collar 25 telescopes within the cylindrical wall 31. Screwed to the upper end of the cylindrical wall 31 is a disk 32 having a central opening 33 through which the rod 20 passes. Cylindrical wall 31 is formed on opposite sides with slots 34.

Each slot 34 comprises a vertical slot portion 35. Extending from the lower end of slot portion 35 is an upwardly inclined offset portion 36. Extending from an intermediate portion of the slot portion 35 is an offset slot portion 37 parallel to slot portion 36. Extending from the upper end of the slot portion 35 is an offset slot portion 38 parallel to slot portions 36 and 37. Slots 34 on opposite sides of the cylindrical casing 31 are similar and symmetrically disposed. The outer end 23 of the pin 22 projects through the slots 34.

Interposed between the collar 25 and the closure disk 32 is a coil compression spring 40. Extending downwardly from the cylindrical wall 31 is an extension 41. Attached to the extension 41 is a loop strap handle 42. Handle 42 may comprise a tubular metal member in loop shape with the outer ends 44 flattened and contacting opposite sides of the extension 41. The flattened portions 44 of the handle are formed with openings registering with openings in the extension 41, and passing through the registering openings are attaching bolts 45.

It will now be understood that for persons of normal height, the pins 23 may extend through the slot portions 36.

If it is desired to pull the hand strap down, the hand strap is first turned so that the pin ends 23 will move into the lower ends of slot portion 35. The hand strap may then be pulled down (compressing spring 40), until the pin ends are registering with the slot portions 37. The

hand strap may then be turned to bring said pin ends into the slot portion 37.

If it is desired to pull the hand strap still further down to accommodate a shorter person, the hand strap may again be turned to bring the pin ends into the slot portion 35, at which time the hand strap may be pulled all the way down (further compressing the spring 40), to bring the pin ends to the upper ends of the slot portion 35. The hand strap can then again be turned to bring the pin ends in the slot portions 33. The strap handle is held in each adjusted position so that the passenger does not constantly feel the pull of the spring.

If it is desired to raise the hand strap, the hand strap is turned to bring the pin ends to the slot portions 35 and then the spring will raise the hand strap to bring the pin ends 23 to the lower ends of the slot portions 35, at which time the hand strap may again be turned to bring said pin ends into slot portion 36.

In Fig. 6 there is shown a device 10a embodying the invention and illustrating a modified construction. The device 10a comprises a member 50 which has a rib portion 19a similar to the portion 19 of Fig. 1, and said portion 19a is provided with a sleeve (not shown) similar to that shown at 11 in Fig. 1.

Extending from rib portion 19a is a shaft 20a at the lower end of which is a head or collar 25a. Slidably mounted on said shaft is a sleeve 30a to the lower end of which may be attached a handle 42 in the same manner as shown in Fig. 1. Screwed to the upper end of the sleeve 30a is a disk 32a formed with a central opening 33a through which the shaft 20 extends.

The opening 33a, however, is formed with a key slot 33b, and fixed to the shaft 20a is a longitudinal key 51 which slides through the key slot 33b to prevent rotation of sleeve 30a relative to shaft 20. Interposed between the head 25a and the disk 32a is a coil compression spring 40a.

It will now be understood that a strap holder may grasp the handle 42 and pull down thereby compressing the spring 40. When the strap holder leaves go the handle the spring 40a will raise the handle. This spring 40a need only be strong enough to lift the handle together with the sleeve 30a.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention I claim as new and desire to secure by Letters Patent of the United States:

1. A device of the character described, comprising a member adapted to be attached to a support, a rod extending therefrom, a collar at the lower end of the rod, a hand strap member, a cylindrical member extending upwardly from the hand strap member and surrounding the rod and collar, a disk at the upper end of the cylindrical member, and a spring interposed between the collar and disk and surrounding the rod and disposed within the said cylindrical member, said cylindrical member being formed with longitudi-

nal slots having a plurality of offset portions, and means extending from the rod and passing through said slots and engageable with said several offset portions of said slots.

5. 2. A member adapted to be attached to a support in a subway or bus, a hand strap member, a rod on one of said members, a cylinder on the other of said members and surrounding said rod, and a coil compression spring surrounding said rod and disposed within said cylinder for raising the hand strap member relative to said first member, said cylinder being formed with a longitudinal slot having spaced offset portions and means on the rod adapted to ride in said slot and engageable within said offset portions.

3. A member adapted to be attached to a support in a subway or bus, a hand strap member, a rod on one of said members, a cylinder on the other of said members and surrounding said rod, and a coil compression spring surrounding said rod and disposed within said cylinder for raising the hand strap member relative to said first member, said cylinder being formed with two spaced apart longitudinal slots having oppositely pointing registering spaced offset branches and projections on said rod, adapted to ride in the respective longitudinal slots and to engage respective branches, upon said rod and cylinder elements being rotated with relation to one another, means fixed to said rod and engaging one end of said spring, and means fixed to said cylinder and engaging the other end of said spring.

4. A member adapted to be attached to a support in a subway or bus, a hand strap member, a rod on said first member, a cylinder on the other of said members and surrounding said rod, and a coil compression spring surrounding said rod and disposed within said cylinder for raising the hand strap member relative to said first member, said cylinder having an end wall with an aperture through which said rod may slide, a head at the inner end of the rod, and said spring being arranged between said end wall and said head, said cylinder being formed with a longitudinal slot having spaced offset branches, and a projection on said rod head, adapted to ride in said slot and engageable within said offset branches.

5. A member adapted to be attached to a support in a subway or bus, a hand strap member, a rod on one of said members, a cylinder on the other of said members and surrounding said rod, and a coil compression spring surrounding said rod and disposed within said cylinder for raising the hand strap member relative to said first member, said cylinder having an end wall with an aperture through which said rod may slide, a head at the inner end of the rod, and said spring being arranged between said end wall and said head, said cylinder being formed with two spaced longitudinal slots having spaced offset opposite registering branches, and two projections on said rod head, adapted to ride in said slots and engageable within respective offset branches.
